BURNHAM C. STICKNEY, OF ELIZABETH, NEW JERSEY, ASSIGNEE TO UNDERWOOD COMPUTING MACHINE COMPANY, OF NEW YORK, N. Y., A CORPORATION OF NEW YORK.

COMBINED TYPE-WRITING AND COMPUTING MACHINE.

1,237,572.

Specification of Letters Patent. Patented Aug. 21, 1917.

Application filed October 20, 1911. Serial No. 655,698.

To all whom it may concern:

Be it known that I, BURNHAM C. STICKNEY, a citizen of the United States, residing in Elizabeth, in the county of Union and State of New Jersey, have invented certain new and useful Improvements in Combined Type-Writing and Computing Machines, of which the following is a specification.

This invention relates to calculating machines combined with writing mechanism, and more particularly to means for determining whether the calculating mechanism shall add or subtract, or remain neutral or ineffective at the operation of the writing mechanism. It also relates to means for shifting the ribbon mechanism so that amounts to be subtracted may be written in a different color from other amounts.

I have provided that the decimal tabulating keys for the typewriter carriage shall be capable of shifting or reversing the action of the computing mechanism, so that, for instance, when the tabulating mechanism is operated to bring the typewriter carriage to position for writing in the first column of numbers on the work sheet, the machine shall be set by such tabulating mechanism to add the number written; when the tabulating mechanism is operated to bring the carriage to the second column of writing on the work sheet, said tabulating mechanism shall reverse the operation of the computing mechanism so that the number written in the second column shall be subtracted; by suitable means the number written in the third column may be added, while the number written in the fourth column may be neither added nor subtracted, and so on as may be desired; the tabulating mechanism having control of the computing devices to determine whether at any particular time they shall add or subtract or remain neutral.

I also preferably connect to the tabulating keys means for shifting the ribbon mechanism, so that the device shall print red or any other special color when writing in a column in which the numbers are being subtracted.

In the accompanying drawings, Figure 1 is a sectional side elevation of an Underwood typewriting and computing machine, having a decimal tabulator, and showing the present improvements applied thereto; the computing mechanism being shown in neutral position or silence, so that

no computation will be performed thereon when the numeral keys are operated.

Fig. 2 should be read in connection with Fig. 1, and shows in elevation many of the new parts that have been added to the tabulating mechanism of the typewriter.

Fig. 3 is a part sectional rear elevation of the typewriting, tabulating and computing mechanisms.

Fig. 4 is a sectional plan view of the computing mechanism and part of the tabulating mechanism.

Fig. 5 is a view similar to Fig. 2, but showing the parts in normal positions.

Fig. 6 is a diagram showing the position of the ribbon shifting mechanism when the machine is in condition for the addition of numbers; the type at this time striking through the black strip of ribbon.

Fig. 7 is a similar view, showing the position when the computing mechanism is silenced; the types still striking through the black ribbon.

Fig. 8 is a similar view, showing the ribbon mechanism shifted so that the types will strike through the red ribbon when subtraction is being performed by the computing mechanism.

The invention is illustrated in connection with a machine in which the computing wheels remain stationary while the master wheel moves step-by-step, being for that purpose connected to the paper carriage of the typewriting machine. This connection is made at the beginning of the writing of each column, and is automatically broken at the conclusion of the writing of each column. The improvements may however be used in connection with other constructions of computing mechanism.

In the Underwood machine, numeral keys 1 depress levers 2 to vibrate bell cranks 3, and swing type bars 4 up to strike rearwardly against the front side of a platen 5. Said platen is mounted on a carriage 6, running on tracks 7, 8, and is driven by a spring barrel 9, and also has a rack 10 meshing with a pinion 11 connected to an escapement wheel 12, the escapement dogs being seen at 12*. The rack 10 is hung on arms 13, so that it may be lifted from the pinion 11 to release the carriage.

Decimal tabulator keys 14 are mounted upon levers 15, which, at their rear ends, raise the stop rods 16, having stops 17 at 110

- their upper ends. These stops may coöperate with interchangeably adjustable column stops 18, inserted, as required, in notches 19, 20, formed in the top and bottom of a bar 21, which is fixed to the carriage 6.
- Each stop-rod has a shoulder 22 coöperating with a universal bar 23, which rocks about a pivot 24, and has an arm 25, which draws down a link 26 and vibrates a lever 27, the latter fulcrumed at 27^a and carrying a roll 27^b to run upon the under side of the rack bar 10, and lift the latter from the escapement pinion 11, whenever a key 14 is depressed.
15. The computing mechanism includes a drive shaft 28, having a bevel pinion 29 meshing with a pinion 30 upon a square shaft 31, the latter being splined to a master-wheel 32, which moves along the shaft and has spurs or teeth 33 to engage an internal set of teeth 34 formed upon a gang of computing wheels 35, the latter mounted in a casing 36 and also having exterior teeth to mesh with gears 38, the latter having number wheels 39. The master-wheel 32 is swiveled in a traveling hollow mandrel or arbor 40, within which the master-wheel shaft 31 may project, the swivel-joint being shown at 41, and permitting the master-wheel 32 to be rotated by the shaft 31, while said master-wheel is caused to travel in axial direction by the mandrel or arbor 40.
- The drive shaft 28 may be driven and controlled either directly by the numeral keys 1 or in any other suitable manner, as for instance in the manner set forth in pending application No. 569,502, filed June 29, 1910. Since the driving means for said shaft form no part of the present invention, it is deemed unnecessary to illustrate the same. The shaft, it will be understood, is rotated automatically upon the depression of any of the numeral keys 1, the extent of rotation depending upon which key is depressed.
45. The mandrel 40 is moved endwise by means of a forwardly and rearwardly extending lever 42, pivoted midway of its ends by means of gudgeons 43, so as to swing in a horizontal plane. At its forward end the lever is slotted at 44 to engage a pin 45 projecting from the carriage which carries the mandrel 40; said carriage comprising a tube 46 sliding upon a fixed rod 47, and also an arm 48, sliding upon a fixed horizontal rod 49; the mandrel 40 being secured to the forward end of the arm 48 by means of a set-screw 50. The movement of the mandrel 40 is of course only sufficient to enable the master-wheel 32 to travel the length of the gang 60 of computing wheels 35, one of which is provided for each number wheel 39. The rod 47 coöperates with two similar rods or studs 49 and 47^a, all projecting from a framework plate or bracket 47^c, to carry a small plate 65 47^d which also supports the end of rod 49,

It will be seen that 49 and 47^b, Fig. 4, carry the casing 36.

At its rear end, the lever 42 has a slot 51 to engage a pin 52 projecting down from a slide 53, the latter carrying the stem 54 of a hook 55, adapted to engage lugs 56 formed upon the blades or stops 18 which are forked to fit into the double rack 19, 20, for connecting the paper carriage 6 to the master-wheel 32 to cause the latter to travel step-by-step with the paper carriage.

The slide 53 works in a tubular guide or housing 58, which is slotted on its under side at 59 to permit the pin 52 to pass down to the lever 42. The stem 54 of the hook 55 passes through a longitudinal perforation in the slide 53, and is adjustably secured to the latter by set screws 60. This permits slight longitudinal adjustment of the hook in order to enable the master-wheel 32 to be 85 adjusted properly relatively to the computing wheels 35 while the hook is engaged by one of the lugs 56. The rack 21 has at 60^a the usual provision for longitudinal adjustment. The slide 53 has a feather 61, to fit 90 into the slot 59, to prevent the slide and the hook from turning in the tube.

The hook 55 has a notch 62 to enable it to engage any of the lugs 56. The hook normally springs up to engage the adjacent lug. 95 For this purpose the hook may be made resilient or flexible, and a compression spring 63 may be employed to aid or cause the upward movement of the hook; said spring 100 housed in a boss 64, and confined by a screw 65, and pressing a plunger 66 up against a straight portion of the under side of the hook, thus holding the latter up while permitting it to move freely endwise. The boss 64 is formed on a bushing 67, which is vertically slotted at 68 to form a guide for the hook; said bushing serving as a plug to close this end of the tubular housing 58.

When the hook is in engagement with one of said lugs 56, it is carried with the 110 paper carriage 6 in letter-feeding direction to cause the lever 42 to swing upon its pivot and thereby drive the mandrel 40 and the master-wheel 32 in the opposite direction. As the keys 1 are operated to write figures 115 in the column, the master-wheel 32 is correspondingly rotated in any usual or suitable manner, to rotate the corresponding computing wheels 35. When the master-wheel has advanced past the computing wheel 35 120 of lowest denomination, a cam 69 formed on the hook 55 engages a projection 70 fixed upon the framework of the machine, and is thereby forced downwardly, to withdraw the hook 55 from that lug 56 with which it 125 has been in engagement. As soon as the hook is released, a returning spring 71 connected to the lever 42 swings the latter in the opposite direction, carrying the master-wheel 32 backwardly, that is, toward the 130

computing wheel 35 of highest denomination; this movement continuing until the hook 55 engages the succeeding lug 56, said hook being pressed up to engage said lug 5 by means of the spring 63, and the hook becoming fully seated in the notch 62. The writing of the numbers in the succeeding column will now proceed, and said number will be accumulated on said computing 10 wheels by the number wheels 39, in the manner already referred to.

When returning the carriage 6 to begin a new line of writing, if the hook 55 is in engagement with one of the lugs 56, it is carried until a cam edge 72 thereon strikes a stud or roller 73, which may be pivoted upon a screw 74, threaded into the top of the boss 64; and by means of said roller or obstruction, the hook is cammed downwardly and released from the lug 56. The spring 63 immediately lifts the hook again, and the lugs 56 in succession ride freely over a bevel or point 75 formed on the tip of the hook; the last lug in the series being caught and held by the hook when the carriage begins to run in letter-feeding direction.

There is provided means for using either color of a bichrome ribbon on the typewriter. Each type bar 4 has a heel 76, which engages with a universal bar 76^a, carried upon a frame 77 which operates escapement dogs 12^a in the usual manner. Upon said universal bar frame 77 is a frame 78 comprising sides 83 which operate the ribbon vibrator 79 by means of pins 80, 81, fast on the lever 82, said pins engaging slots in frame 78, so as to cause said lever 82 to swing about its pivot 82^a in the usual manner. Said vibrator is described in detail in co-pending case above referred to. The color used is determined by the position of the pins 80, 81, which serve to turn lever 82 operating said vibrator 79 about its fulcrum. If the upper pin 80 is used, the throw of the vibrating lever 82 is small, and only the upper part of the ribbon comes between the type and the platen. This is usually black. If the lower pin 81 is used, the throw is much greater and the lower part of the ribbon comes between the type and the platen. This is usually red.

The arrangement of said pins is clearly shown in elevation in Fig. 3, and in plan in Fig. 4. Here it will be seen that they are adapted to be engaged by either of the sides 83 of universal bar frame 77, shiftable by 87 of shaft 88, having the usual color-keys 89 and 90. These keys then may set the 60 color of the ribbon.

Also pivoted to said arm 87 is a link 91, which, through bell crank 92 and link 93, is moved by arm 94 fast on control shaft 95. This shaft in a manner hereinafter described, is moved automatically through the

movements of the tabulating keys to control the computing mechanism, while through the connections just described, it controls also the ribbon color.

Control shaft 95 carries an arm 96, which, through link 97, connects it to bell crank or clutch-controller 98, on an arm 99 of which latter is a pin 100, controlling double clutch 101. This clutch 101 is splined to shaft 28, but is movable up and down by said pin 100 to engage with upper or lower pinion 29 and cause pinion 30 to drive master wheels 32; or said clutch 101 may occupy an intermediate position and be idle. It is obvious that pinion 30 can thus be driven in either direction, and said master wheel 32 may either be idle, add or subtract, as fully described in the co-pending application above referred to. Said bell crank 98 may be moved by a handle 102 fast on it, and through link 97 above described, this handle will also move control shaft 95 and set the ribbon mechanism.

Means are provided for operating control shaft 95 automatically at the actuation of the tabulator keys so that work of a tabular nature can be done involving mixed operations of adding and subtracting, without any attention on the part of the operator beyond pressing the tabulator keys after the typewriter is set for the given kind of work.

Mounted above rack bar 21 and pivotally supported at 104 at each end of the carriage, is a leaf 103 controlled by the tabulator keys to set the parts for adding or subtracting or to be neutral as the case may be and to simultaneously shift the ribbon to its appropriate color. An arm 105 of a bell crank 106 pivoted in the main frame at 107 is arranged to bear against leaf 103, and by arm 108 turns control shaft 95, which latter controls the ribbon and computing mechanism. A returning spring 108^a presses arm 108 outward, and consequently arm 105 down upon said leaf. Said leaf 103 is moved up by the rack release link 26, and therefore by the returning tabulator keys, through an arm, rest or jack 109 pivoted on lever 110, which latter is pivoted to rack release link 26 at 112 and fulcrumed on the main frame at 111. Said arm 109 is pulled by a spring 113 against a pin or rest 114 which guides it, and said spring will always raise said arm when the tabulator key is released, so that pawl 115 or 116 near its upper end 117 may strike on an edge of leaf 103, if it falls within its line of travel.

In Fig. 3 is shown leaf 103 raised (as viewed from the back) and in Fig. 2 it is shown in the same position in section. Parts 125 of the edge are cut away as at 118, 119, 119, while parts 120, 120 are of full width. Said full width parts 120 are adapted to be struck by pawl 116 as it ascends and so raise leaf 103 which will move the parts to the posi- 130

tion shown in Fig. 2. In this position, arm 105 has risen and rotated control shaft 95, so that the machine will subtract. This would shift the parts shown in Fig. 1 by 5 moving arms 94 and 96 to the right, raising clutch 101 to engage with upper spur 29, and simultaneously slide 83 of the ribbon color changing mechanism would assume the position in Figs. 3 and 4.

10 If jack 109 is raised by depressing a tabulator key when the carriage is so positioned the part 118 of the leaf 103 (cut to an intermediate height) is opposite jack 109, then lower pawl 115 will be the only part of said 15 jack whose line of travel will fall within said leaf 103, and the leaf will be raised to the intermediate position shown in Fig. 1. In that position control shaft will be so turned that clutch 101 will be neutral, and 20 the ribbon will write black.

At Fig. 5, a tabulator key is depressed, and the jack 109 is opposite a deeply cut-away portion 119 of the leaf 103. When, therefore, the tabulator key is released, and 25 jack 109 allowed to rise, it will do so without striking leaf 103, because the latter is at this point cut away to 119. In that case, jack 109 will rise idly above leaf 103, and the normal condition of the computation-controlling mechanism will not be disturbed.

In order to prevent the leaf 103 from fouling with the jack 109, the transition from one edge to another in the width of leaf 103 is made by bevels, as shown in Fig. 3, at 121, 35 121, which will press jack 109 out in passing it, and so prevent the machine from being injured or the carriage from being locked.

The operation of the machine is as follows: With the carriage set as in Fig. 3, 40 near the beginning of a line, the operator has pressed and released a tabulator key, whereby control shaft 95 has been moved to pull back link 97, causing clutch 101 to engage with the upper pinion 29 and drive the 45 computing mechanism to subtract. At the same time, said shaft 95 has moved slide 83 (as viewed in Fig. 4) to the left, to engage pin 81 and bring the red portion of the ribbon into operation. Accordingly the type 50 keys are operated to write the number in red, which number is subtracted by the totalizer.

By pressing and releasing another tabulator key, the carriage is shifted to the second column-stop. Leaf 103 is cut away at 119 55 so it will not be caught by either pawl of 109, but remains as shown in Fig. 5. Arm 105 is held down by spring 108, and control shaft 95 and clutch 101 remain in position for the computing mechanism to add, and 60 arm 94 on said shaft holds the ribbon mechanism in position for writing black. The desired numbers are then written, and added in. Then a tabulator key is pressed, and the carriage is brought to rest against the third 65 stop. Jack 109 rises with the release of the

tabulator key, and strikes its pawl 116 against the portion 118 of 103. This will raise said leaf to the position shown in Fig. 1, and arm 105 will shift control shaft 95 so as to move clutch 101 to neutral position, 70 so that numerals written will not be recorded in the computing mechanism. Control shaft 95 likewise moves the rod 85 of ribbon shifting mechanism, but not sufficiently to cause the ribbon to change, so the color remains black. 75

Other similar results follow the pressing of tabulating keys, till the end of the line is reached. In the machine as illustrated, the last operation is subtraction. If the carriage at the end of a line is now pushed back by hand, the broad part of leaf 103 will ride on pawl 116 of jack 109 till a narrow part of 119 of said leaf is reached. Then said leaf 103 will fall into its lowest position, 85 completely free of jack 109 and the carriage may be moved to begin the next line; the parts resuming their normal addition positions.

Normally the leaf, in its lowest or addition position, rests on stops 122, and the keys 89 and 90 or the handle 102 may be used to control any desired computing operation or ribbon color, provided a tabulator key is not depressed. Or if leaf 103 is 90 removed, the combined machine may be used as a computing machine with manual ribbon shift, and manual computing mechanism shift.

None of the figures shows all the parts in 100 normal positions. At Fig. 5 the leaf 103 is in normal position, but the jack 109 is shown in its lowest position. The normal position of this jack is the same as at Fig. 2, but in this figure the leaf is shown swung up. 105 Whenever any tabulator key is depressed, the jack is drawn down from normal position idly to the position seen at Fig. 5; the pawl edges riding over the edge of the leaf. As the jack reaches its lowest position, the 110 spring 113 snaps it under the leaf 103 (which at this time is in its normal position); whereby all of the parts are brought to the Fig. 5 position. While they are in this position, the carriage travels until arrested by contact of the next column-stop 18 with that 115 denomination stop 16 which has been elevated at the tabulating operation. The tabulator key is then released, restoring the control of the letter-feeding mechanism over 120 the carriage, and also permitting spring 113, aided by the returning spring usually coiled around shaft 24 (Fig. 1) to lift the jack 109, together with the leaf 103, to the Fig. 2 position; in which position these parts remain during the ensuing movement of the carriage in letter feeding direction (with the computing mechanism shifted to subtraction and the ribbon mechanism to write red) until the end of the ledge 120 is reached, 125 130

whereupon the leaf trips off from the jack and drops to normal position, the color of the ribbon changing to black, and the computing mechanism returning to addition condition. If after the completion of any tabulating operation there should be a gap in the leaf above the jack, the latter, of course, will not, when rising, affect the leaf, but the latter will remain in normal addition position. If at any time the operator should desire to set the carriage back to write in any column, the preferable method would be to run the carriage back an excessive distance, and then use the tabulating mechanism to bring the carriage to the desired position, so as to get the benefit of the condition-controlling function of the tabulating mechanism and hence have the color of the ribbon right and the computing mechanism in the right condition for working in that column. Another method would be, after setting the carriage back to the desired column, to hold the carriage with one hand against traveling, while the other hand depresses a tabulating key, no movement of the carriage taking place, but the computing mechanism and the ribbon being both properly set by the tabulating key.

It will be seen that my invention is not limited to mere adding and subtracting mechanisms, but that the controlling means could be readily used for a machine performing other operations, and that it is not limited to two-colored ribbons.

35 Variations may be resorted to within the scope of the invention and portions of the improvements may be used without others.

Having thus described my invention, I claim:

40 1. In a combined typewriting and computing machine, a typewriter carriage, an adding and a subtracting mechanism, a link controlling said mechanism, a control shaft moving said link, a leaf on the carriage of the typewriter, a tabulator key to control the setting of said leaf, an arm moved by said leaf, and a second arm connecting said arm to said control shaft.

50 2. In a combined typewriting and computing machine, a carriage, a leaf movable on said carriage, tabulator keys coöperating with stops to release and set said carriage, means moved by said tabulator keys to control said leaf, and an arm moved by said leaf to shift the mechanism.

55 3. In a combined typewriting and computing machine, a decimal tabulating device, a mechanism to perform more than one kind of computation, and means controlling said mechanism, said controlling means dependent upon the movement of the tabulating device.

60 4. In a combined typewriting and computing machine, a typewriter carriage, a mechanism capable of doing more than one kind

of computation, a tabulating key, a jack moved to inoperative position by said key, a pawl on said jack, a leaf on the typewriter carriage having parts adapted to be intercepted by said pawl, a spring moving said jack to operative position, an arm governed by said leaf, and a shaft moved by said arm to control the computing mechanism.

5. In a combined typewriting and computing machine, a typewriter carriage, a mechanism capable of doing more than one kind of computation, a decimal tabulating device having keys, a leaf on said carriage controlled by the keys of said tabulating device, a shaft, an arm on the shaft, a bell crank 75 moved by the leaf on the carriage to move said arm and means moved by the shaft to control the computing mechanism.

6. In a combined typewriting and computing machine, a typewriter carriage, a mechanism adapted to perform more than one kind of computation, a decimal tabulating device having keys, a leaf on said carriage, a jack moved by the keys of said tabulating device to control said leaf, a 85 shaft to control the computing mechanism, and an arm on the shaft moved by said leaf to govern the computing mechanism.

7. In a combined typewriting and computing machine, a typewriter carriage, a mechanism adapted to perform more than one kind of computation, a decimal tabulating device having keys, a leaf on said carriage, a jack moved by the keys of said tabulating device to control said leaf, a 95 shaft to control the computing mechanism, an arm moved by said leaf, and a link connecting said shaft to said arm.

8. In a combined typewriting and computing machine, computing mechanism, a control mechanism for said computing mechanism, a typewriter carriage including an escapement and a rack, a tabulating device, a rack release, coöperating with said tabulating device, an arm moving with said rack release, a leaf on the carriage, a jack moved by said arm to set said leaf, an arm moved by said leaf, and a shaft moved by said second arm to control said computing mechanism.

9. In a combined typewriting and computing machine, typewriting and computing mechanisms and a carriage, connections between said typewriting and computing mechanisms, a control mechanism for said 120 connections comprising a leaf on said carriage, a spring, a jack moved by said spring to set said leaf, a key for moving said jack out of the path of said leaf to reset it, and a control arm set by said leaf.

10. The combination with a carriage and tabulating mechanism therefor, of computing mechanism including means for determining whether the computing mechanism shall add or subtract, and means connected to 130

said tabulating mechanism to operate after the advance of the carriage and when the tabulating operation has been completed, for operating said determining means.

5 11. The combination with a carriage and tabulating mechanism therefor, of computing mechanism including means for determining whether the computing mechanism shall add or subtract, and means connected 10 to said tabulating mechanism to operate after the advance of the carriage and when the tabulating operation has been completed, for setting said determining means and maintaining it in the adjusted position during the ensuing traverse of the computing zone by the carriage.

12. The combination with a letter-feeding carriage and a computing mechanism capable of performing either addition or subtraction, of means normally inoperative during the run of the carriage, for determining whether the computing mechanism shall perform addition or subtraction, a tabulating mechanism, and means operatively connected 20 with said tabulating mechanism for actuating said determining means and controlling it during a predetermined length of travel of the carriage.

13. The combination with a letter-feeding carriage and a computing mechanism capable of performing either addition or subtraction, mechanism including a master wheel, of means normally inoperative during the run of the carriage, for determining whether the computing mechanism shall perform addition or subtraction, a tabulating mechanism, and means operatively connected with 30 said tabulating mechanism for actuating said determining means, and causing the latter to be effective during a predetermined length of travel of the carriage.

14. In a combined typewriting and computing machine, a typewriter carriage, a mechanism capable of doing more than one kind of computation, a decimal tabulating device, a leaf on the carriage, means dependent upon the movements of the tabulating device for moving said leaf out of normal position relatively to said carriage, and means for controlling the computing mechanism set by the leaf.

15. In a combined typewriting and computing machine, a typewriter carriage, a mechanism capable of doing more than one kind of computation, a decimal tabulating device, a device coöperating with the carriage for positioning the computing columns, a leaf on the carriage, and means dependent upon the movements of the keys of the tabulating device for causing said leaf to control the computing mechanism.

16. In a combined typewriting and adding machine, a carriage, tabulator mechanism therefor including keys, and a leaf dependent upon the movements of the tabulator

keys for converting the machine into a subtracting machine, said mechanism also capable of being moved into a neutral position by said leaf.

17. The combination with a carriage and tabulating mechanism therefor, of computing mechanism capable of performing either addition or subtraction, a normally inoperative device upon the carriage for determining whether the computing mechanism shall add or subtract, a member to engage said carriage device and set it to effective position, and means dependent upon the movements of the tabulating mechanism for controlling said member.

18. The combination with a carriage and tabulating mechanism therefor, of computing mechanism capable of performing either addition or subtraction, a normally inoperative device upon the carriage for determining whether the computing mechanism shall add or subtract, a member to engage said carriage device and set it to effective position and hold it there during travel of the carriage, and means dependent upon the movements of the tabulating mechanism for controlling said member.

19. The combination with a carriage and tabulating mechanism therefor, of computing mechanism capable of performing either addition or subtraction, a normally inoperative device upon the carriage for determining whether the computing mechanism shall add or subtract or be neutral, a member to engage said carriage device and set it to effective position, and means dependent upon the movements of the tabulating mechanism for controlling said member.

20. The combination with a step-by-step feeding carriage and tabulating mechanism therefor, of computing mechanism including a master wheel, said computing mechanism including a portion connected to said carriage to travel therewith, a device upon the carriage to coöperate therewith for determining whether the machine shall add or subtract, a member to engage said carriage device and set it to effective position and hold it there during travel of the carriage in letter-feeding direction, and means dependent upon the movements of the tabulating mechanism for controlling said member.

21. A computing machine, combining a traveling carriage, a bichrome ribbon, numeral keys, types operated therefrom to print through said ribbon, a computer operated from the numeral keys to register an item simultaneously with the printing thereof, a member carried by the carriage and having movement relatively to said carriage, means controlled by said member when moving relatively to said carriage for changing the state of the computer and altering the color of the ribbon and means dependent upon the carriage travel for effect-

- ing the automatic return of said member relative to the carriage to thereby effect return of the computer to its original state and the return of the ribbon to its original 5 color.
22. A computing machine combining a traveling carriage, a bichrome ribbon, numeral keys, types operated therefrom to print through said ribbon, a computer operated from the numeral keys to register 10 an item simultaneously with the printing thereof, a manually operable device carried by the carriage and movable relatively thereto, means for repeatedly moving said device relatively to the carriage during 15 each run of the carriage and effective at each operation to alter the state of the computer and color of the ribbon and means controlled in accordance with the position 20 of the carriage for effecting the automatic return of said member to normal position with respect to said carriage to thereby alter the state of the computer and the color 25 of the ribbon repeatedly during each run of the carriage.
23. A computing typewriter including polychrome printing mechanism, a register, an actuator therefor, a traveling carriage for bringing one denomination after another of said register under the control of 30 the actuator, a member mounted on said carriage and movable relatively thereto, means settable by hand at the will of the operator to move said member relatively 35 to the carriage to thereby change the character of the arithmetical operation performed and change the color of the printing, and means controlled by said carriage for automatically restoring said member to 40 normal position relatively to said carriage.
24. A computing typewriter combining polychrome typewriting mechanism including a carriage, computing mechanism for registering numbers written by said typewriting mechanism and including means 45 settable to add or subtract the numbers written, a spring for normally holding said settable means set for addition, a latch for holding said settable means for subtraction, 50 and means controlled by said carriage for tripping said latch.
25. In a combined typewriting and computing machine, the combination with numeral keys of computing mechanism and a 55 carriage controlled by said keys, a device moving with the carriage, said device also having a movement relative to said carriage, tabulating keys, mechanism convertible to coöperate in different ways with said 60 numeral keys to affect the character of the computation and means brought into action on operation of a tabulating key for positioning said carriage and moving said device relative to said carriage to convert 65 said mechanism.
26. In a machine of the class described, the combination of numeral keys, a typewriter carriage, a mechanism convertible to coöperate in different ways with said keys, means for converting said mechanism, 70 a link moving said converting means, a leaf on the carriage of the typewriter and movable relatively thereto, a tabulator key setting said leaf relatively to said carriage, and an arm connected to said link and 75 moved by said leaf to operate said converting means.
27. In a machine of the class described, the combination of numeral keys, a typewriter carriage, a mechanism convertible 80 to coöperate in different ways with said keys, links controlling said mechanism, a control shaft moving said links, an arm on said shaft for moving the same, a leaf on the carriage of the typewriter, a tabulator 85 key controlling the setting of said leaf, and an arm on the main frame, moved by said leaf and moving said arm on said shaft.
28. In a combined typewriting and computing machine, the combination of numeral keys, a typewriter carriage, a mechanism convertible to coöperate in different ways with said keys, means to control said convertible mechanism, a tabulating device, 90 a leaf pivoted on the carriage of the typewriter, a jack controllable by the tabulating device, said jack capable of supporting said leaf, and an arm on the main frame moved by said leaf to operate said controlling means.
29. In a machine of the class described, the combination of numeral keys, a typewriter carriage, a mechanism convertible to coöperate in different ways with said keys, a tabulating key, a jack moved by said 95 key, lugs on said jack, a leaf on the typewriter carriage having parts adapted to rest on said lugs, an arm governed by said leaf, and means moved by said arm to convert said convertible mechanism.
30. In a machine of the class described, the combination of numeral keys, a typewriter carriage, a mechanism convertible to coöperate in different ways with said keys, a tabulating key, a jack moved by said 100 key, lugs on said jack, a leaf on the typewriter carriage having parts adapted to be intercepted by one of said lugs, and also having parts adapted to sweep clear of at least one of said pawls, an arm governed by said leaf, and a shaft moved by said arm to control the conversion of the convertible mechanism.
31. In a combined typewriting and computing machine, the combination with numeral keys, of a carriage, a computing mechanism convertible to addition, subtraction or 115 neutral condition, a pivoted leaf connected to travel with said carriage, and means to engage said leaf and swing it to convert said 120
- 125
- 130

computing mechanism, said leaf comprising a broad portion, a narrow portion, a diagonal connecting said broad and narrow portions, a still narrower portion, a diagonal 5 connecting said still narrower portion, said converting means including a part to engage said portions.

32. In a combined typewriting and computing machine, numeral keys, a typewriter carriage, a tabulating mechanism therefor including a key, a mechanism convertible to coöperate in different ways with said keys, and means to convert said convertible mechanism, comprising a leaf mounted on 10 the carriage of the typewriter, a jack for holding said leaf in given positions, and an arm on the main frame controlling the convertible mechanism and moved by said leaf, said leaf being resettable by said tabulating 15 key.

33. A computing typewriter including typewriting numeral keys, a carriage, a computing mechanism coöoperative with said keys, a bichrome mechanism also coöoperative with said keys, each of said mechanisms convertible to coöperate in different ways with said keys, said computing mechanism comprising an actuator and a register, means settable to change the character of the arithmetical operation performed by the computing mechanism, and concomitantly convert 25 said bichrome mechanism to a different condition, a spring for normally holding said settable means in one position, a latch for holding said settable means in another position, a sliding bar for operating said latch, and means whereby the travel of the carriage operates said bar.

34. A machine of the class specified, combining a step-by-step feeding carriage, numeral keys, a device operated from the numeral keys and convertible to coöperate therewith in different ways, and tabulating mechanism for said carriage, said convertible device being convertible by said tabulating mechanism, and said carriage having means effective through the travel thereof, for securing the automatic return of the convertible device to its original state after the 40 tabulating operation.

35. A computing typewriter including printing mechanism, a register, an actuator therefor, a traveling carriage for bringing one denomination after another, of said register under the control of the actuator, a member mounted on the carriage and movable relatively thereto, means settable by hand at the will of the operator to move said member relatively to the carriage to thereby 45 change the character of the arithmetical operation performed by said register and means controlled by said carriage for automatically restoring said member to normal position relatively to said carriage.

36. A computing typewriter combining

numeral type keys, a carriage controlled thereby, a computing mechanism convertible to different states and coöperating with said keys, a device movable relatively to the carriage for converting said computing 70 mechanism repeatedly during each run of the carriage, and means dependent upon the movement of the carriage for automatically restoring said device to normal position repeatedly during each run of the carriage. 75

37. A computing typewriter combining numeral type keys, a carriage controlled thereby, a computing mechanism for coöperation with said numeral keys, a device movable relatively to the carriage for setting 80 said computing mechanism to neutral position so that it will not compute at the operation of said keys, and means to enable said carriage to restore said device to condition to enable said computing mechanism to operate at the operation of said keys.

38. A computing typewriter combining numeral type keys, a carriage controlled thereby, a computing mechanism for coöperation with said keys, a device movable 90 relatively to the carriage for converting said computing mechanism to an opposite state at one part of the run of said carriage, and to a neutral state at another part of the run of said carriage, and means dependent upon the run of said carriage and effective during a single run thereof, for restoring said device and thereby said computing mechanism from its opposite state and also from its neutral state. 95

39. A combined typewriting and computing machine having a carriage, type operating numeral keys, computing mechanism capable of coöperation with said keys and convertible from a state to perform addition to 105 either a state to perform subtraction or a neutral state, means for determining the characteristic of the printing effected by said numeral keys, said characteristic-determining means convertible from one to another of two conditions, and connected with the convertible computing mechanism to operate under one condition for one state of said computing mechanism, and under the other condition for either of the remaining 110 two states thereof, and means dependent upon the movement of said carriage for restoring the characteristic-determining means to original condition and concomitantly restoring the computing mechanism to its normal state from either of the remaining 115 states. 120

40. In a combined typewriting and computing machine, the combination with a carriage, of a convertible computing mechanism, a manually operable member, and means under the joint control of said carriage and said manually operable member, for effecting a succession of conversions of 125 said computing mechanism during a single 130

run of said carriage, said carriage having means for determining the character of the conversions, and said manually operable member having means for effecting the 5 conversions.

41. In a combined typewriting and computing machine, the combination with a carriage, of a computing mechanism convertible to different states, a manually operable member, and means under the joint control of said carriage and said manually operable member, for effecting a succession of conversions of said computing mechanism during a single run of said carriage, said carriage having means for determining the character of the conversions, and said manually operable member having means for effecting the conversions, and provision dependent upon the travel of the carriage being also 10 made for effecting the restoration of the computing mechanism to normal condition 15 a succession of times during each run of the carriage.

42. In a combined typewriting and computing machine, the combination with a carriage, of a computing mechanism convertible to addition, subtraction or neutral position, a manually operable member movable relatively to the carriage to determine when 20 the computing mechanism shall be converted, and means dependent upon the position of the carriage and said movable mem- 25

ber for determining the character of each of a succession of conversions during a single run of the carriage.

43. In a combined typewriting and computing machine, the combination with a carriage, of a computing mechanism convertible to addition, subtraction or neutral position, a manually operable member to determine when the computing mechanism shall be converted, means dependent upon the position of the carriage for determining the character of each of a succession of conversions during a single run of the carriage, 40 and means dependent upon the progress of the carriage during its single run for returning the computing mechanism to normal condition from such of the two conditions to which it may have been converted by said 45 manually operable member.

44. In a combined typewriting and computing machine, the combination with numeral keys and computing wheels, of means whereby said keys cause said wheels to either 50 add or subtract, a latch for holding said means at subtracting position, tabulating keys, and a universal bar operated by said tabulating keys for controlling said latch.
